UNITED STATES PATENT OFFICE.

WILLIAM F. ELLIS, OF STAMFORD, CONNECTICUT.

RAILROAD CROSS-TIE.

SPECIFICATION forming part of Letters Patent No. 769,068, dated August 30, 1904.

Application filed September 19, 1903. Serial No. 173,878. (No model.)

To all whom it may concern:

Be it known that I, WILLIAM F. ELLIS, a citizen of the United States, residing at Stamford, in the county of Fairfield and State of Connecticut, have invented new and useful Improvements in Railroad Cross-Ties, of which the following is a specification:

The object of my invention is to provide a metallic tie and tie-plate which will combine to form a durable yet light cross-tie structure and at the same time provide for a degree of resiliency equal to that of the wooden tie.

To this end the invention consists in forming the tie proper in the form of an inverted arch and supporting a tie-plate on the bearing edges thereof in such manner as to produce resiliency by causing the walls of the tie to spread when the tie is subjected to pressure from weight on the rails.

The invention also consists in certain novel features in the construction and arrangement of parts, all as hereinafter described, and specifically pointed out in the appended claim.

In the accompanying drawings, Figure 1 is a top view of the combined tie and tie-plates as applied to the rails. Fig. 2 is a view in which a rail is shown in side elevation and cross-sectional view shown of the tie, taken on the line 2 2, Fig. 1. Fig. 3 is a longitudinal section taken on the line 3 3, Fig. 1. Fig. 4 is a top view of a portion of the tie. Fig. 5 is a top view of two coöperating tie-plates.

Referring to the drawings, 6 designates the tie, which is in the form of an inverted arch having outwardly-extending supporting flanges 7 and is preferably constructed of structural steel in order to provide the necessary resiliency to the walls thereof. The tie at the point of junction with the flanges is curved outwardly, as at 8, producing a flared bearing extremity to the walls of the arch, which bearing portion will be brought into operation with the tie-plate 9 when pressure is applied to said plate. The tie-plate comprises a pair of coöperating like elements, each consisting of a metallic strap turned under at each end to form flange-embracing hooks 10 and having a centrally-inturned hook 11, formed integral with the strap, which is adapted to embrace the base-flange 12 of the rail 13 and may be hammered into close contact

with the base-flange when the rails are placed in position. The hooks 10 of the combined tie-straps are received in the notches 14 in the flanges of the tie, which notches not only hold 55 the plate against lateral displacement, but also hold both sections of the plate together on the rail.

In practice the two inside sections of the tie-plates are first placed in their proper position 60 on the tie, with the rail-hook embracing the rail, the tie being compressed to draw the flanges together in order to admit of this operation. The rails are thus secured so that the outside sections of the tie-plates can be 65 snugly positioned on the rails, after which the tie is again compressed to receive said outside sections within their respective notches 14.

In the present invention when the tie-plates are depressed the flared or curved bearing- 70 surfaces 8 continuing into the flanges 7 spring inwardly under the weight upon the rails in view of the connections established by the tie-plates 9. In this manner a cushioning effect is obtained, and at the same time the load is 75 equally distributed on every part of the tie.

Having thus described the invention, what I claim as new is—

A railroad-tie, comprising a resilient U-shaped arch having horizontally-disposed outwardly-projecting flanges extending full length of the tie, the opposite walls of the tie merging into the flanges flaring outwardly in curved lines, said flanges having slots at diametrically opposite points therein near the 85 ends, and a tie-plate disposed horizontally over and bearing upon the flanges adjacent to each opposed pair of slots, the said tie-plates being bent downwardly through the slots and under the flanges and also provided with centrally-upstanding inwardly-projecting rail-engaging hooks, the terminal downwardly-bent ends of the tie-plates being of such length as to permit yielding movement of the arch without disengaging the ends of the tie-plates 90 from the flanges which they engage. 95

In testimony whereof I affix my signature in presence of two witnesses.

WILLIAM F. ELLIS.
